UNITED STATES PATENT OFFICE.

ANTONI CIESLIK, OF LORAIN, OHIO.

NETHERGARMENT.

1,225,578.

Specification of Letters Patent.

Patented May 8, 1917.

Application filed January 26, 1917. Serial No. 144,697.

To all whom it may concern:

Be it known that I, ANTONI CIESLIK, a subject of the Czar of Russia, residing at Lorain, in the county of Lorain and State of Ohio, have invented certain new and useful Improvements in Nethergarments, of which the following is a specification.

This invention relates to garments and has special reference to a nether garment. More particularly the invention relates to trousers.

One important object of the invention is to provide an improved construction of trousers which are so arranged that means are provided whereby bagging at the knees of the trousers is prevented in a novel and improved manner.

A second important object of the invention is to provide an improved construction of trousers having certain attachments thereto which will permit and effect drawing up of the trousers upon the wearer assuming a seated position.

A third important object of the invention is to provide an interior attachment for trousers of novel construction which, during wear of the trousers will act, when the wearer assumes a seated position, to draw the trousers up and prevent knees being formed while the attachment may be detached for the purpose of pressing the trousers when desired.

With the above and other objects in view, as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:—

Figure 1 is a front elevation of a pair of trousers constructed in accordance with this invention.

Fig. 2 is a longitudinal median section through one leg of the trousers, the section being broken away in parts.

Fig. 3 is a transverse section on the line 50 3—3 of Fig. 1.

Fig. 4 is a view similar to Fig. 2 but showing the condition of the trousers when the wearer is seated.

Fig. 5 is an enlarged detail section of the 55 upper end of the trouser leg showing the

arrangement to enable the elastic element used herewith to be detached.

In carrying out the objects of the invention in the form herein illustrated there is shown a pair of trousers 10 having legs 11 and inside of the upper part of the trousers and extending down each leg to a point about three inches above the knee is a lining 12 which is preferably made of sillesia or other like non-adhering material and this lining is secured at its lower end by means of a stitched line 13. Furthermore, on either side of the front median line of each leg the lining is secured to the leg by a stitched line 14 so that a pocket 15 is formed between the lining and the front of the leg. At the upper and lower end of each leg, and in alinement with the pocket 15 there is provided a loop 16 which is fixedly secured in position so that it may receive the spring hooks 17 which are fixedly connected to the upper and lower ends of a strip of elastic webbing 18. This elastic webbing has its warp threads of rubber or other elastic material while the woof threads are formed of some such material as wool or the like so that the webbing will adhere to the material of the trousers inside of the legs.

Now it will be seen that by reason of the slippery lining of each leg the upper part of each leg may move freely over the under garments since it will not adhere thereto. At the same time when the wearer sits down the elastic webbing will adhere to the material of the trousers to a sufficient extent to draw the front of the trousers upward as shown in Fig. 4 while at the same time the elasticity of the webbing will permit of sufficient yielding to prevent any undue stress being placed on the material of the trousers which tends to tear it. It will be obvious that when a person arises the knee will no longer force the webbing into intimate contact with the material of the trousers and consequently the trousers will drop and resume their original position.

There has thus been provided a simple and efficient garment of the kind described and for the purpose specified.

It is obvious that many minor changes may be made in the form and construction of the invention without departing from the material principles thereof. It is not therefore desired to confine the invention to

the exact form herein shown and described but it is wished to include all such as properly come within the scope claimed.

Having thus described the invention, 5 what is claimed as new, is:—

1. The combination with a pair of trousers; of a lining for the legs of said trousers constructed of non-adherent material and terminating above the knee portion of 10 the trouser legs, said lining being secured at its lower end portions to said legs and being further secured to the trouser legs on each side of the front median line of each leg to form a pocket in connection 15 with the material of the trousers, and elastic webbings each extending through a pocket and down the front of a trouser leg, each webbing being secured at its upper and lower ends to the trousers, the warp 20 threads of said webbings being of elastic material and the woof threads being formed of material adapted to adhere to the material of the trousers.

2. The combination with a pair of trou-

sers; of a lining for the legs of said trousers constructed of non-adherent material and terminating above the knee portion of the trouser legs, said lining being secured at its lower end portions to said legs and being further secured to the trouser legs on each side of the front median line of each leg to form a pocket in connection with the material of the trousers, and elastic webbings each extending through a pocket and down the front of a trouser leg, 30 the warp threads of said webbings being of elastic material and the woof threads being formed of material adapted to adhere to the material of the trousers, loops fixed at the top and bottom seams of the trousers, 35 and hooks carried by the ends of the webbings and engaging the loops.

In testimony whereof I have affixed my signature.

ANTONI CIESLIK.
